DESIGN FOR A WALL HEATER

Raymond L. Fitch, Los Angeles, Calif., assignor
to The Firan Co., Santa Monica, Calif., a cor-
poration of California

Application July 19, 1947, Serial No. 140,401

Term of patent 14 years

(Cl. D81—10)

To all whom it may concern:

Be it known that I, Raymond L. Fitch, a citizen of the United States of America, residing in the city of Los Angeles, in the county of Los Angeles, State of California, have invented a new, original, and ornamental Design for a Wall Heater, of which the following is a specification, reference being had to the accompanying drawing, forming a part thereof.

Figure 1 is a perspective view of a wall heater;

Figure 2 is a front elevational view thereof,
showing my new design;

Figure 3 is a side elevational view of the same;
and

Figure 4 is a rear elevational view of the heater.

I claim:

The ornamental design for a wall heater, sub-
stantially as shown.

RAYMOND L. FITCH.
